UNITED STATES PATENT OFFICE

EDWARD E. WHITMORE, OF CHICAGO, ILLINOIS, ASSIGNOR TO THE ADLAKE COMPANY,
OF CHICAGO, ILLINOIS, A CORPORATION OF ILLINOIS

CURTAIN FIXTURE

Application filed January 4, 1929. Serial No. 330,171.

The present invention is concerned with curtain fixtures of the same general type as that disclosed in Whitmore Patent No. 1,036,045, wherein the curtain to which the fixture is attached constantly tends to wind up on a roller under the action of a torsion spring and the fixture is mounted in the lower end of the curtain and is provided with retractable members which engage frictionally within guides at the sides of the frame to prevent the curtain from being wound up.

The purpose of the invention is to provide an improved curtain fixture which is absolutely noiseless and will prevent the curtain from working upwardly.

While the foregoing statement is indicative of the nature of the invention, other objects and advantages will be evident upon a full understanding of the novel construction, arrangement and operation of the fixture.

In order that the invention may be readily understood, one form of the same is presented herein, but it will of course be appreciated that such form is merely intended for the purpose of illustration and that the invention is capable of being embodied in other structurally modified forms coming equally within the scope of the claims.

In the accompanying drawing:

Fig. 1 is a top view of the fixture;

Fig. 2 is a side view of the same;

Fig. 3 is a sectional view through one end of the fixture, both ends of which are the same, showing the guide-gripping member in retracted position; and

Fig. 4 is a corresponding view, showing the guide-gripping member in operation.

As will be observed in the drawing, the fixture includes a tube 10 which is adapted to be encased in the lower end of a spring-wound window curtain. The tube carries two heads 11 and 12 which are adapted to ride up and down in two grooved guides 13 and 14 attached to the opposite sides of the associated window frame. The heads are provided with tubular portions 15 which slidably fit within the ends of the tube, and with upper and lower rollers 16 which are adapted to bear without friction against the bottoms of the grooves in the guides. The heads are pressed

outwardly with respect to the ends of the tube by coil springs 17 which are compressed between washers 18 seated against the inner ends of the tubular portions of the heads and other washers 19 seated against the outer sides of constrictions 20 in the tube.

The tube also carries two rods 21 and 22. The inner ends of the rods are in screw-threaded engagement with two finger-pieces 23 and 24 which project through axially elongated slots 25 and 26 in a plate 27 secured to the tube over an opening in the center of the same. The outer ends of the rods slidably fit within the tubular portions of the heads and carry two substantially arc-shaped cams 28 and 29. The cams are pivoted eccentrically to the ends of the rods at 30 and do not have any connection whatever with the heads. The cams are symmetrical in construction above and below the pivotal axes thereof, and the upper portions 31 serve to wedge frictionally against the bottoms of the grooves in the guides to prevent the lower end of the curtain from moving upwardly. The lower portions 32 of the cams perform the same function as the upper portions when the heads are reversed, and also serve to wedge frictionally with the bottoms of the grooves in the guides should any downward force be applied to the lower end of the curtain to prevent it from being moved downwardly unless the finger pieces 25 and 26 have first been pinched together. The cams are limited in the extent to which they may turn about their pivotal axes by means of diverging upper and lower shoulders 33 on the cams which move into abutment with the upper and lower sides of the rods adjacent the ends of the latter. It will be appreciated of course that the lower portions 32 of the cams may be dispensed with without in any way affecting the action of the upper portions in holding the lower end of the curtain against upward movement.

When the finger pieces 25 and 26 are pinched together, the cams are retracted by the rods into positions clear of the guides, as shown in Fig. 3, and when the finger pieces are released, after the lower end of the curtain has been raised or lowered into the desired

position, the cams are projected outwardly under the actions of the springs 17 and, upon engaging with the bottoms of the grooves in the guides, are caused to rock into frictional wedging engagement with the guides, as shown in Fig. 4.

The rods 21 and 22 are movable independently of the heads, and vice versa, but the extent of relative movement therebetween is limited by means of pins 34 which extend diametrically through the rods into axially elongated slots 35 in the tubular portions of the heads. The heads, being entirely independent of the cams, are not in any way affected by the operation of the latter and remain at all times in spring-pressed frictionless engagement with the bottoms of the grooves in the guides. Because of this, the fixture in its normal position is absolutely noiseless, both the rollers in the heads and the cams at the ends of the rods being held snugly against the bottoms of the grooves in the guides by spring action.

I claim:

1. In a curtain fixture, a tube adapted to be secured to the lower end of a spring-wound window curtain, outwardly spring-pressed heads at the ends of the tube adapted to engage with guides at the sides of the frame in which the curtain is mounted, outwardly spring-pressed rods, extending through the tube into the heads, and members mounted and operating independently of the heads on the ends of the rods in frictional engagement with the guides.

2. In a curtain fixture, a tube adapted to be secured to the lower end of a spring-wound window curtain, outwardly spring-pressed heads at the ends of the tube adapted to engage with guides at the sides of the frame in which the curtain is mounted, outwardly spring-pressed rods, extending through the tube into the heads, and curved cam members eccentrically pivoted to the outer ends of the rods independently of the heads for frictional wedging engagement with the guides independently of the heads under the upward moving tendency of the curtain.

3. In a curtain fixture, a tube adapted to be secured to the lower end of a spring-wound window curtain, outwardly spring-pressed heads at the ends of the tube adapted to engage with guides at the sides of the frame in which the curtain is mounted, outwardly spring-pressed rods, extending through the tube into the heads, curved cam members eccentrically pivoted to the outer ends of the rods independently of the heads for frictional wedging engagement with the guides independently of the heads under the upward moving tendency of the curtain, and means to limit the rocking movement of the cam members with respect to the rods.

4. In a curtain fixture, a tube adapted to be secured to the lower end of a spring-wound

window curtain, outwardly spring-pressed heads at the ends of the tube adapted to engage with guides at the sides of the frame in which the curtain is mounted, outwardly spring-pressed rods extending through the tube into the heads, curved cam members eccentrically pivoted to the outer ends of the rods independently of the heads for frictional wedging engagement with the guides under the upward moving tendency of the curtain, and means acting between the cam members and the rods to limit the rocking movement of the cam members with respect to the rods.

5. In a curtain fixture, a tube adapted to be secured to the lower end of a spring-wound window curtain, outwardly spring-pressed heads at the ends of the tube adapted to engage with guides at the sides of the frame in which the curtain is mounted, outwardly spring-pressed rods, extending through the tube into the heads, curved cam members eccentrically pivoted to the outer ends of the rods independently of the heads for frictional wedging engagement with the guides under the upward moving tendency of the curtain, and shoulders on the cam members for engagement with the rods adjacent the ends thereof to limit the rocking movement of the cam members with respect to the rods.

In witness whereof I have hereunto subscribed my name.

EDWARD E. WHITMORE.
